United States Patent Office.

ALBERT REED, OF MANKATO, MINNESOTA.

Letters Patent No. 67,073, dated July 23, 1867.

IMPROVED LATH-FRAME.

The Schedule referred to in these Letters Patent and making part of the same.

TO ALL WHOM IT MAY CONCERN:

Be it known that I, ALBERT REED, of Mankato, Blue Earth county, Minnesota, have invented a new and improved Lath-Frame; and I do hereby declare that the following is a full, clear, and exact description thereof, which will enable others skilled in the art to make and use the same, reference being had to the accompanying drawings, forming part of this specification.

The present invention relates to a frame so constructed as to facilitate the nailing and securing of laths to the side of a room, and at regular and equal distances apart, so as to leave spaces or openings of a uniform size or width between the several rows or series of laths. In the accompanying plate of drawings my improved lath-frame is illustrated—

Figure 1 being a front view of and elevation of the same.

Figure 2 is a transverse vertical section, taken in the plane of the line x x , fig. 1.

Similar letters of reference indicate corresponding parts.

A, in the drawings, represents my improved lath-frame, which consists of two parallel uprights, B, joined together at each end and at the centre by cross-bars or braces C. The two uprights B upon both sides are provided with a series of projecting pins or studs, D, at equal and regular distances apart from the upper to the lower end of the frame, with the several pins of both uprights in the same horizontal lines or planes. On these pins the laths are placed one above another, so that if the frame either previously or afterwards be placed against the side wall of a room, and there secured by the screw-bolt E, through its centre, with the laths against the side of such room, by then nailing such laths thereto, they can be all secured at uniform distances apart, so as to leave equal and regular spaces or openings between them; the frame, after the laths have been all nailed, being then unfastened and removed by pulling it away from the wall.

I claim as new, and desire to secure by Letters Patent—

A lath-frame constructed substantially as and for the purpose described.
